UNITED STATES PATENT OFFICE.

JONATHAN HALEY, OF FOSTORIA, OHIO.

DESIGN FOR A TOOTHPICK-HOLDER.

SPECIFICATION forming part of Design No. 20,186, dated October 7, 1890.

Application filed August 25, 1890. Serial No. 363,049. Term of patent 9½ years.

To all whom it may concern:

Be it known that I, JONATHAN HALEY, a citizen of the United States, and a resident of Fostoria, county of Seneca, State of Ohio, 5 have invented a new and useful Improvement in Designs for Glassware, (for three years and six months,) of which the following is a full, clear, and exact description, reference being had to the accompanying drawing, making part of this specification.

My invention relates to a new design in glassware for a toothpick-holder, the novel feature of which consists in the form and ornamentation of the particular piece of glass- 15 ware hereinafter described and illustrated.

The accompanying drawing is a perspective illustrating my design.

The base A consists of a right-lined quadrilateral having rounded ends, said base having a plane vertical side and end portion, surrounded by an oval diagonally-fluted border B, extending about the base. On the plateau of said base is shown a two-wheeled vehicle, a wheel a shown on the front side of the

drawing and a similar wheel on the opposite 25 side. Between the two wheels and integral therewith is a quadrilateral box or body portion C, constructed in imitation of vertical board-work b, secured by strips c, about the top and bottom and corners of the imitation 30 board-work. At the front end of said cart and integral therewith is a quadruped D, as shown, having thereon a harness c, integral with said quadruped and said cart, comprising a bust and shoulder strap and tug, as 35 shown. On the plateau of said base A, under the said quadruped, is a plant of the class *Syngenesia*.

What I claim as new, and desire to secure by Letters Patent, is—

The design for a toothpick-holder, as herein shown and set forth.

In testimony whereof I have hereunto set my hand this 15th day of July, A. D. 1890.

JONATHAN HALEY.
